UNITED STATES PATENT OFFICE.

ELLA LOUISE SMITH, OF ROANOKE, ALABAMA.

ATTACHABLE EAR FOR DOLLS.

1,292,113.

Specification of Letters Patent.

Patented Jan. 21, 1919.

Application filed September 13, 1918. Serial No. 253,864.

To all whom it may concern:

Be it known that I, ELLA LOUISE SMITH, a citizen of the United States, residing at Roanoke, in the county of Randolph and

5 State of Alabama, have invented certain new and useful Improvements in Attachable Ears for Dolls, of which the following is a specification.

My invention relates to improvements in 10 attachable ears for dolls, and it consists in the combinations, constructions and arrangements herein described and claimed.

The present invention is designed to be an improvement over that disclosed in my prior

15 Patent No. 800,333. In said prior patent I disclosed a doll having a head composed partly of fabric. The ear of the doll, in the prior patent, was sewed to the head. The work of sewing the ear required considerable 20 time and the present invention is designed to provide an attachable ear which may be quickly and accurately secured in place, and which will remain in place permanently.

A further object of my invention is to 25 provide an ear which is made of plastic material which can be readily attached to any doll head having fabric as a part of its composition, or a stuffing of material such as cotton.

30 Other objects and advantages will appear in the following specification, and the novel features of the invention will be particularly pointed out in the appended claims.

My invention is illustrated in the accompanying drawing, forming part of this application, in which—

Figure 1 is a side view of a doll with the ear attached in position;

Fig. 2 is a section along the line 2—2 of 40 Fig. 1;

Fig. 3 is a view showing the ear in position to be applied; and

Fig. 4 is a detailed sectional view showing a modified form of the device.

45 In carrying out my invention I make a molded ear 1 of any suitable plastic composition, such as plaster of Paris. The ear is provided with two openings, or perforations 2. The securing means consists of a 50 staple 3 whose prongs are provided with bars 4.

In Fig. 2 I have shown a section of a doll's head which consists of a fabric or composition shell or exterior 5 with an interior stuff- 55 ing of cotton 6.

In applying the ear the barbed prongs of the staple are passed through the openings and pushed through the exterior shell into the stuffing on the interior. The prongs of the staple are preferably provided with a 60 number of barbs so that each barb engages a portion of the stuffing, or the interior wall of the shell, thereby holding the ear securely into position. The work of attaching the ear is very slight, it only being necessary to 65 place the ear in the proper position and to push the staple inwardly, thereby obviating the necessity of sewing all around the ear, as in the prior patent.

It may sometimes happen, however, that 70 it is inconvenient to get a staple of this character, and in such case, especially where the head is made of flexible fabric, as for instance with rag dolls, the ear may be sewed by passing thread 7 through the openings 2 75 in the manner shown in Fig. 3. This, however, is a much more simple procedure than to sew all around the ear.

In either case the ear is secured permanently to the head and, as stated before, in 80 the case of the staple, it may be done almost instantly.

I claim:

1. The combination of a doll's head, an attachable ear therefor consisting of molded 85 plastic material, said ear having a pair of openings, and a staple arranged to pass through the openings and into the head for securing the ear to the head.

2. The combination of a doll's head, an attachable ear therefor made of unyielding 90 material and provided with a pair of openings, and a barbed staple arranged to pass through the openings and into the head and to engage portions of the head thereby 95 firmly securing the ear to the head.

3. The combination of a doll's head, an attachable ear therefor made of unyielding material and provided with a pair of openings, and a staple provided with a plurality 100 of barbs on each prong arranged to pass through the openings and into the head, the different barbs engaging different portions of the head whereby the ear is firmly secured to the head.

105 In testimony whereof I affix my signature.

ELLA LOUISE SMITH.
